UNITED STATES PATENT OFFICE.

STEPHEN G. WILSON, OF PHILADELPHIA, PENNSYLVANIA.

BROOM.

1,392,384.

Specification of Letters Patent.

Patented Oct. 4, 1921.

Application filed April 24, 1919. Serial No. 292,253.

To all whom it may concern:

Be it known that I, STEPHEN G. WILSON, a citizen of the United States, residing in the city and county of Philadelphia, State of Pennsylvania, have invented a new and useful Broom, of which the following is a specification.

My invention consists of a broom which is provided with a butt or stub, a portion of which is adapted to enter the head of the broom material and to be retained therein, said butt being adapted to have the handle or stick proper of the broom to be connected therewith whereby the angle of the handle may be varied according to requirements or desirability.

It consists also in adapting said butt to be reinforced in the direction of its length by means of plates of rigid material, portions of which are inserted in slots in the butt, and another portion thereof being inserted in slots in the handle and secured in the respective members.

It consists also of a box which is adapted to be connected with the aforesaid butt and with the body of the broom proper as practical, strong and durable means intermediate of the handle and body of the broom proper for connecting said body and handle and permitting the latter to be changed in angularity.

It consists also of a cap on the head of the body of the broom, and a box intermediate of said body and handle of the broom, said box and broom being provided with novel means of connection.

It consists also in providing the aforesaid box with means whereby its sides may be firmly connected with the butt or stub employed.

It consists also of a washer interposed between the box employed and the broom handle so as to provide a close joint for said members while readily permitting the change of angularity of the handle.

It consists also in providing said washer and the head of said box with slots through which the reinforcing plates employed for the butt and the broom handle may pass.

It consists also of details of construction as will be hereinafter described and pointed out in the claims.

The invention is satisfactorily illustrated in the accompanying drawing, but the important instrumentalities thereof may be

varied, and so it is to be understood that the invention is not limited to the specific details shown and described, as long as they are within the spirit or scope of the claims.

Figure 1 represents a perspective view of a portion of a broom embodying my invention.

Figs. 2 and 3 represent perspective views of detached portions thereof.

Fig. 4 represents a vertical section of a portion of a broom embodying my invention.

Fig. 5 represents a vertical section thereof at a right angle to Fig. 4.

Fig. 6 represents a perspective view of a box or head employed.

Fig. 7 represents a perspective view of a washer or gasket employed.

Figs. 8 and 9 represent perspective views of members of said box or head in separated condition. Fig. 10 represents a top view of a detached portion.

Similar numerals of reference indicate corresponding parts in the figures.

Referring to the drawings,

1 designates a portion of the main handle or stick of a broom, and 2 designates a section of a stick that I denominate as a butt or stub, the lower end portion of which is inserted in the top or head 3 of the body 4 of the broom of approved broom material.

In said butt are the longitudinally-extending slots 5 which extend a certain length therein being open at top and sides and closed at the bottom, which latter is above the lower end of the butt. Inserted in said slots are the plates 6 of metal or other suitable rigid material, the same being extended above said butt and inserted in slots 7 in the broom handle or stick 1, the upper ends of said plates 6 being pointed as at 6^x so that they may be driven into the solid portion of the handle or stick above said slots 7 so as to be held firmly therein.

The lower end portion of the handle is fitted in the socket 8, and is firmly secured thereto by the rivet 9 which is passed transversely through said socket, the handle 1, and the plates 6, the ends of said rivet being headed on the side of the socket, thus firmly and compactly connecting said members as most clearly shown in Fig. 5.

10 designates a box consisting of the curved head 11, the fixed sides 12 depending therefrom, and the loose or movable sides 13 which are somewhat resilient and interposed

between the fixed sides 12, said box being adapted to receive the upper portion of the butt 2.

The lower end of the stick is seated on the 5 washer 14 of pliable or flexible material, the ends of which are upwardly flanged as at 14^x and adapted to embrace the lower end of the socket 8, see Fig. 4, said washer being seated on the upper side of the head 10 of the box 10.

15 designates a pivot consisting of a pin which is passed transversely through the movable sides 13 of the box, the stub 2 and the plates 6, its ends being threaded and having thereon the thumb nuts 16 whereby the movable sides 13 of the box may be drawn tightly against the side of the stub, said pivot connecting the stick 1 with the butt 2 forming the axis of the stick on 20 said butt.

In the washer 14 are slots 17 and in the head 11 of the box are the slots 18 which freely receive adjacent portions of the plates 6, and permit the handle to turn on the butt, 25 the washer to ride on the head 11 in the turning of the handle, and the portions of the plates 6 in the slots 18 of said head to play therein, as the stick describes its pivotal or turning motions, it being noticed 30 that the lower end of the stick 1, the upper end of the butt and said washer are concentrically curved whereby said stick owing to its pivot 15 may turn laterally on said head, and so change its angularity for 35 required or desired purposes, as will be hereinafter stated.

On the inner side of the upper portions 40 of the movable plates 13 of the box 10 are the inwardly projecting beads 13^x which are segmental in length and adapted to have 45 bearings on the adjacent portions of the butt 2 and so cause said portions of said plates to bear firmly against the butt 2 and adapting the remainder of said plates 13 to be forced inwardly against the butt by the action 50 of the thumb nuts 16 on the pivotal pin 15, and tightly compressing the sections of the slotted stub and the plates 6 in the latter.

55 On the lower ends of the sides 12 of the box are the outturned tongues 19 which are adapted to engage the hollow cap 20 which is fitted over the top or head 3 of the body of the broom, as shown in Fig. 4, it being noticed that the top of said cap has therein an opening the walls of which form the horizontal flanges 21, said opening permitting the lower portion of the butt 2 to pass through the same and so enter and occupy 60 said top of the body of the broom, while at the same time the tongues 19 of the box are sprung against the underside of said flange 21, thus connecting said cap with said box, and vice versa.

65 On the side of the butt at about the bot-

tom of the slots 5 therein are the upturned shoulders 22, which form between the latter and the adjacent portion of the butt the recesses 23, which are adapted to receive the lower ends of the movable sides 13 of the 70 box 10, assisting to retain said ends in position on the butt, said shoulders also preventing improper outward motion of said ends of the sides 13 of the box, it being noticed that the shoulders and consequently the recesses 23 are below the flange 21 of the 75 cap 20.

Depending from the lower end of the cap are devices 24 and 25 for connection with other members on the body of the broom, 80 the same being the subject matter of another application for Letters Patent filed by me on or about the 20th day of July, 1918, Serial No. 245,856.

The elongated slots 26 in the plates 13 in 85 which the pivot pin 15 is received permit said plates to be lowered and so pressed tightly against the bases of the recesses 23, while the lower ends 12^x of the sides 12 of the box rest upon the flanges 21 around the 90 opening in the top of the cap 20. Then the walls 13 of the box contacting with the inner faces of the walls 12 of said box force the tongues under said flanges 21, said tongues being somewhat bent whereby they 95 are resilient, and so engage effectively with said flanges. By these means the stub and consequently the handle are firmly braced or stiffened in their connection with the body of the broom, and so prevented from 100 lateral motion on said body and vice versa.

As the body of the broom and the stub, and consequently the stick are firmly connected, I avoid sewing of the lower portion 105 of said body, the sewing or stitches 27 in the upper portion of the said body, holding together said portion sufficiently for all purposes of compactness.

The sides of the movable walls 13 of the box 10 have thereon inturned flanges 28 110 which contact freely with the inner faces of the fixed walls 12 of said box, thus guiding said walls 13 in their motions and steadyng them when set in adjusted position.

The lower portions of the plates 6 are tapering as at 6^{xx} whereby the plates are permitted to turn to a sufficient extent without being materially stopped by the lower portions of the walls 12 of the box, this being 120 also permissible by the bore being made of tapering form.

I employ a plurality of plates 6 so as to brace the stub 2 and prevent bending of the same, said plates being formed of thin metal or other material without adding much weight to the stub.

The lower ends of the sides of the movable walls 13 extend below the lower ends 130 of the sides 12 thereof, whereby the former

may be seated on the base of the recesses 23 in the stub.

As the plates 13 are tapering when they are pushed down to full extent their lower portions are adapted to tighten against the walls of the hollow cap 20, and so they are held firmly in said cap and prevented from lateral turning.

An opening 29 is formed in the sides of 10 the box 10 as a finger piece for conveniently moving said box to its adjusted position.

Having thus described my invention what I claim as new and desire to secure by Letters Patent, is:—

15 1. In a broom, a box with slots, a butt therein with its lower portion inserted in the body of the broom and its upper end extended beyond the said broom body and disposed in said box, a reinforcing plate in the butt, a pivot passed through the box, butt and plate, said plate inserted in the handle, and means to hold the parts in angular position.

20 2. In a broom, a box, a butt therein with its lower portion inserted in the body of the broom and its upper end extended beyond the said broom body and disposed in said box, a reinforcing plate in the butt, a pivot passed through the box, butt and plate, said plate inserted in the handle, and means to hold the parts in angular position, said box having a curved head having slots to engage said plate and the broom handle having a correspondingly curved coöperative portion.

25 3. In a broom, a box, a butt therein with its lower portion inserted in the body of the broom and its upper end extended beyond the said broom body and disposed in said box, a reinforcing plate in the butt, a pivot passed through the box, butt and plate, said plate inserted in the handle, and means to hold the parts in angular position, said box having a curved head having slots to engage said plate and the broom handle having a correspondingly curved coöperative portion, and a yielding member interposed between said curved surfaces.

4. In a broom, a box, a butt therein with its lower portion inserted in the body of the broom and its upper end extended beyond the said broom body and disposed in said box, a reinforcing plate in the butt, a pivot passed through the box, butt and plate, said plate inserted in the handle, and means to hold the parts in angular position, said box having a curved head having slots to engage said plate and the broom handle having a correspondingly curved coöperative portion, and a hollow cap fitted over the top of the broom body and coöperating with said box.

5. In a broom, a box, a butt therein with its lower portion inserted in the body of the broom and its upper end extended beyond the said broom body and disposed in said

box, a reinforcing plate in the butt, a pivot 65 passed through the box, butt and plate, said plate inserted in the handle, means to hold the parts in angular position, said box having a curved head having slots to engage said plate and the broom handle having a 70 correspondingly curved coöperative portion, and a hollow cap fitted over the top of the broom body and coöperating with said box, the box and cap having coacting flanges.

6. In a broom, a box connectible with the 75 head of the body of the broom, a butt adapted in part to occupy said box and in part to occupy said head, a broom handle, a reinforcing plate continuous in said handle and butt firmly held therein and adapted to connect said butt and handle, and a pivotal member in said box, butt and plate adapting the handle to change its angularity.

7. In a broom, a handle, a butt connected with the handle and having its lower portion occupying the head of the body of a broom, a box connected with said head and having movable sides, a pivot passed through said movable sides and butt, and means coöperating with said pivot for drawing the movable sides against said butt.

8. In a broom, a handle, a butt connected with the handle and having its lower portion occupying the head of the body of a broom, a box connected with said head and having movable sides, a pivot passed through said movable sides and butt, and means coöperating with said pivot for drawing the movable sides against said butt, said movable sides being provided with inwardly-projecting beads to engage adjacent faces of the butt.

9. In a broom, a butt having a portion adapted to occupy the head of the body of the broom, a broom handle adapted to be 105 connected firmly with said butt, and a box slotted for the passage of the butt and handle connecting means and adapted to receive the upper portion of said butt and to be connected therewith and constituting a 110 portion of the joint, said box being adapted to be connected with the head of the body of the broom and having movable sides, means for connecting said butt and box to a handle, and means pivotally connected to the 115 butt and box for connecting the same to the handle, the compression of the sides of the box also serving to clamp said connecting means between the handle and butt.

10. In a broom, a butt having its lower 120 portion adapted to occupy the head of the body of the broom, a broom handle, a continuous plate in said handle and butt firmly connected therewith, a box in which the upper portion of said butt is contained, a 125 pivoted member in the side of said box and in said butt and plate connecting said handle with said butt and permitting the former to

change its angularity, the top of said box having therein slots in which the adjacent portion of said plate is movable.

11. In a broom, a butt adapted in part to occupy the head of the body of a broom, rigid reinforcing means in said butt and extended beyond one end thereof, means having slots and receiving said reinforcing means, said means embracing the butt and forming a support for the pivot of the handle, and a handle in which the upper ends of said reinforcing means are received, and means securing said reinforcing means and handle together.
12. In a broom, a butt having its lower portion adapted to occupy the head of the body of the broom, and a box adapted to contain the upper portion of said butt and constituting a portion of the joint, said box having fixed and movable sides, the movable sides being provided with flanges which are adapted to be inturned on the inner faces of the fixed sides of the box, and means for connecting said butt and box to a handle.

13. In a broom, a butt having its lower portion adapted to occupy the head of the body of the broom, and a box adapted to contain the upper portion of said butt, and means for connecting said butt and box to a handle, said box constituting a portion of the joint and having therein a finger receiving opening to admit of the convenient movement of the box in its adjustments.

14. In a broom, a butt having its lower portion adapted to occupy the head of the body of the broom, and a box adapted to contain the upper portion of said butt, said box constituting a part of the hinge joint between the handle and the butt, said box having fixed and movable sides, the lower ends of the movable sides extending below the movable ends of the fixed sides, and means for connecting said butt and box to a handle.

STEPHEN G. WILSON.
